UNITED STATES PATENT OFFICE.

EUGENE R. EDSON, OF CLEVELAND, OHIO, ASSIGNOR TO THE EDSON REDUCTION MACHINERY COMPANY, OF AUGUSTA, MAINE, A CORPORATION OF MAINE.

APPARATUS FOR DISPOSING OF FOUL VAPORS.

SPECIFICATION forming part of Letters Patent No. 714,165, dated November 25, 1902.

Application filed January 20, 1902. Serial No 90,552. (No model.)

To all whom it may concern:

Be it known that I, EUGENE R. EDSON, a citizen of the United States of America, residing at Cleveland, in the county of Cuyahoga and State of Ohio, have invented certain new and useful Improvements in Apparatus for Disposing of Foul or Ill-Smelling Vapors and Gases; and I hereby declare the following to be a full, clear, and exact description of the invention, such as will enable others skilled in the art to which it pertains to make and use the same.

This invention relates to improvements in apparatus for disposing of foul or ill-smelling vapors and gases emanating from material which is being dried or reduced or rendered.

The primary object of this invention is to prevent the said vapors and gases from contaminating the external air.

Another object is to provide apparatus of the character indicated which is simple in construction, readily taken care of, and reliable in its operation.

With these objects in view the invention consists in certain features of construction and combinations of parts hereinafter described, and pointed out in the claims.

In the accompanying drawings, Figure I is a side elevation, partly in section, of apparatus embodying my invention. Fig. II is a side elevation, largely in central section, of a condenser which forms a portion of the apparatus. Fig. III is a side elevation in central section of a tank wherein the gases insoluble in water are separated from the soluble gases and vapors. This figure is a view looking at the side of the tank opposite to the view of the said tank shown in Fig. I. Figs. II and III are drawn on a larger scale than Fig. I.

Referring to the drawings, *y* represents the receptacle wherein the drying or reduction of material from which foul gases and vapors emanate or arise takes place. The receptacle *y* is provided at the top with a vapor-outlet *z*, which is connected by a valved pipe *5* with the water-receiving chamber *6* of a condenser *x*. The valve *7* of the pipe *5* is normally closed. The pipe *5* communicates with the

chamber of the condenser, preferably near the lower end of the said chamber, and adjacent to the condenser has a convolution *9*, arranged in a vertical plane and extending, preferably, above the condenser or at least 55 adjacent to the upper end of the condenser, so that the passage of water from within the condenser through the said pipe *5* is avoided. The valve *7* is of course opened, if not already open, preparatory to the operation of the apparatus, so that gases and vapors arising or emanating from any material being treated within the receptacle *y* are conducted by the pipe *5* into the condenser.

The condenser is provided at the bottom 65 with a drain-pipe *8*, which is in open relation with the lower end of the aforesaid chamber of the condenser and extends downwardly from the condenser into the body of water or liquid within a well or subterranean reservoir *w*, and obviously any water discharged into the condenser and instrumental in effecting a condensation or liquefaction of vapors and gases conducted into the condenser by the pipe *5* and any liquid forming in the 75 condenser by such condensation pass into the drain-pipe *8* and by the said drain-pipe are conducted into the well or reservoir *w*.

The well or reservoir *w* at a suitable elevation above its lower end communicates with 80 a pipe *h*, adapted to connect with or feed a sewer, and obviously water or liquid flows from the said reservoir or well to the sewer when the water-level within the said well or reservoir rises to a point opposite and above 85 the bottom of the inlet of the said pipe.

The well or reservoir *w* is preferably closed at its upper end by a cover *10*, and the drain-pipe *8* is formed by two sections joined by a union *12* above the cover *10* with the lower 90 section extending through the cover into the said reservoir, and obviously the said cover can be readily removed upon disconnecting the said lower pipe-section from the upper pipe-section of the drain-pipe by properly manipulating and thereby rendering the union 95 *12* inoperative.

The condenser is provided at its upper end and centrally with an outlet for gas and vapors not condensed or liquefied within the 100

condenser, and the said outlet is connected by a pipe *v* with the inlet of the pump *t*.

A valved water-supply pipe 13 connects with the condenser at a suitable elevation 5 above the discharging end of the pipe 5 and has a normally closed valve 14, which is of course opened preparatory to the operation of the condenser. The water-supply pipe 13 discharges, as shown in Fig. II, into a slotted 10 pipe-section 15, within and arranged transversely of the upper end of the chamber 6 of the condenser. The pipe-section 15 is closed at its inner end, as at 16, and embraced and supported at the said end by an annular 15 flange 17, formed upon and internally of the casing of the condenser. The pipe-section 15, in each side thereof, has two slots 18, arranged to discharge laterally of the chamber of the condenser and extending longitudinally 20 and from end to end of the said pipe-section. Obviously, therefore, the water conducted to the condenser by the pipe 13 is discharged in sheets transversely of the chamber 6 by the water-distributing pipe-section 25 15 during the operation of the condenser, and upon opening the valve 7 of the pipe 5, if the said valve has not already been opened, and operating the pump *t* a partial vacuum or suction is created within the condenser, and 30 gas and vapors emanating or arising from the material undergoing treatment within the receptacle *y* and accompanying air are pulled or drawn from the said receptacle *y* through the pipe 5 into the condenser and upwardly 35 through the sheets of water discharged from the pipe-section 15, and obviously any gases and vapors condensed or liquefied within the condenser gravitate with the water discharged into the condenser into the pipe 8 and are 40 conducted by the said pipe 8 to the well or reservoir *w*, as already indicated.

Gases and vapors and accompanying air not condensed or liquefied within the condenser and passing through the pipe *v* into 45 the pump *t* are discharged by the pump into a valved pipe *s*, which is connected with the outlet of the pump; but the valve *q* of said pipe is of course opened, if not already open, preparatory to the operation 50 of the pump. The pipe *v* conducts the vapors and gases and accompanying air received thereby to a tank *a*, which is preferably in the form of a cylinder arranged in a horizontal plane. The chamber of the tank 55 *a* is supplied with water preparatory to the operation of the apparatus, and a depth of water, having the water-level within the upper portion of the said tank, is maintained during the operation of the apparatus. The 60 tank *a* is shown very clearly in Fig. III.

The water-inlet of the tank *a* is preferably formed by a pipe-fitting *b*, which is attached to the bottom of the tank *a*, centrally between the ends of the tank, and is in open relation 65 with the water-receiving chamber in the tank.

A valved branch *c* of the water-supply pipe 13 connects and is in open relation with the

pipe-fitting *b* and has its valve *d* normally closed.

A valved drain-pipe *e*, having its valve *f* 70 normally closed, extends from the pipe-fitting *b* to the waste-pipe *g* and is attached to the said waste-pipe and to the said pipe-fitting.

The waste-pipe *g* extends above and below 75 the drain-pipe *e*, extending downwardly below the said drain-pipe to and communicating with the well or reservoir *w* and extending upwardly above the said drain-pipe to the top of the tank *a*, where it (the said waste-pipe *g*) communicates with the chamber of the said tank at one end of the tank and at the elevation of the level of water which obtains within the tank during the operation of the apparatus. 80

By the construction hereinbefore described the tank *a* is supplied with water or drained according as the valve *d* of the pipe *c* or the valve *f* of the pipe *e* is opened; but of course the valve *f* is only opened when the tank *a* 90 needs cleaning internally.

The foul or ill-smelling vapors and gases which are to be disposed of and to the best advantage are conducted into the body of water within the tank *a* during the operation 95 of the apparatus, and such of the said gases and vapors as are soluble in the water are absorbed into and diffused throughout the body of water and conducted off with the water flowing into the waste-pipe *g*. 100

The valve *d* of the pipe *c* is of course opened and left open during the operation of the apparatus, and the supply of water to the tank *a* is so regulated by the valve *d* that a continuous flow of liquid from the said tank 105 into the waste-pipe *g* obtains during the operation of the apparatus.

Any gases and air conducted into the tank and not soluble in or conveyable off with the water flowing from the tank into the waste-pipe are disposed of preferably by conducting them to the ash-pit of a furnace and there causing them to pass through the grate into the combustion-chamber next over the grate, where they are consumed and facilitate 115 the combustion.

Fig. I of the drawings shows a furnace *i*, and *j* designates the combustion-chamber of the furnace, *k* the grate, and *l* the ash-pit below the grate. A pipe *m* has its discharging 120 end arranged within the ash-pit and extends from the furnace to the top of the tank *a*, where it is in open relation with the chamber of the said tank. The waste-pipe *g* communicates with the chamber of the tank *a* at an 125 elevation somewhat below the inlet of the pipe *m*, so that there is no liability of water entering the pipe *m*, which extends, preferably, somewhat above the tank. The waste-pipe *g* extends, preferably, into the body of 130 liquid in the reservoir *w*, below the sewer-feeding pipe *h*, so that liquid from the said reservoir will enter and form a liquid seal in the discharging end portion of the said pipe

and prevent gases and vapors which enter the said pipe, but do not enter the solution with the liquid flowing into or through the pipe, from escaping through the said pipe. Hence 5 any gases and vapors or air received within the tank *a* and not carried off in solution with the water flowing from the tank escape from the tank into the pipe *m*, by which they are conducted to the furnace for consumption.

10 The means employed for introducing gases and vapors into the tank *a* comprises a perforated pipe-section *n*, arranged within and longitudinally of the lower portion of the chamber of the said tank. The pipe-section *n* is supported in any approved manner and extends through one end wall of the tank *a* to the other end wall of the tank, being closed at its inner end, as at *o*. The pipe-section *n* has its lower portion provided at short intervals longitudinally of the same with orifices *r*. The pipe-section *n* is connected and in open relation at its outer or receiving end with the discharging end of the pipe *s*, which, as already indicated, is in open relation with 15 the outlet of the pump *t*, which is shown arranged at an elevation below the tank *a*. The pipe *s*, outside of and next adjacent to the tank *a*, has a convolution *u* arranged in a vertical plane and extending, preferably, 20 above the tank *a*, or at least above the water-level maintained within the tank during the operation of the apparatus, so that water cannot be conducted from the tank through the said pipe *s*.

25 The location of the perforated pipe-section *n* in close proximity to the bottom of the chamber of the tank *a* is important, because thereby the gases and vapors are introduced into the body of water within the said chamber farthest below the outlets of the chamber, and any soluble, gaseous, or aeriform body passing into the said body of water will likely have been absorbed or diffused in the water before it reaches the said outlets, so that only 30 gases and air not soluble in water will pass from the tank into the pipe which conducts the said last-mentioned gases and air to the furnace.

It will be observed that the pumping of the 35 gases and vapors and accompanying air into the tank *a* and any suction created by a draft through the furnace materially expedite or facilitate the passage of gases to the furnace. It is evident, therefore, that by the apparatus hereinbefore described foul or ill-smelling 40 gases and vapors and odors emanating or arising from a body of material undergoing treatment within the receptacle *y* are successfully disposed of without contaminating 45 the external atmosphere, and a large portion of the said gases and vapors and the accompanying air are utilized to advantage. I would remark also that the extension of the drain-pipe 8 of the condenser into a body of 50 water or liquid is not unimportant, because thereby water or liquid is drawn into the said pipe a suitable distance by and during the

operation of the pump, and the partial vacuum or suction created by the operation of the said pump is not interrupted or interfered with, and it is obvious, of course, that the column of liquid extending into the said pipe from the body of liquid rises or lowers according as more or less suction is created by the operation of the pump. 70

The process disclosed in this application is claimed in an application, Serial No. 90,716, filed January 21, 1902.

What I claim is—

1. The combination, with the receptacle 80 wherein gases and vapors arise or emanate from material treated therein, a pump, a well or reservoir supplied with a body of liquid, and a pipe adapted to connect with or feed a sewer and extending from the well or reservoir a 85 suitable distance above the lower end of the said well or reservoir, of a condenser having a chamber in open relation, at its upper end, with the inlet of the pump; a drain-pipe in open relation with the lower end of the said 90 chamber and extending into the aforesaid body of liquid below the sewer-feeding pipe; means for distributing water within the aforesaid chamber a suitable distance above the drain-pipe; a water-supply pipe arranged to 95 feed water to the said water-distributing means, and a pipe arranged to conduct gases and vapors from the first-mentioned receptacle to the condenser and arranged to discharge into the aforesaid chamber of the condenser. 100

2. The combination, with a receptacle wherein gases and vapors arise or emanate from material treated therein; of a pump, a condenser having a water-receiving chamber, 105 a well or reservoir at an elevation below the condenser; a drain-pipe extending from the lower end of the said chamber into the well or reservoir, means for distributing water within the said chamber a suitable distance 110 above the drain-pipe, a water-supply pipe arranged to feed water to the water-distributing means, a pipe connected with the aforesaid chamber between the drain-pipe and the water-distributing means and in open relation 115 with the chamber of the first-mentioned receptacle at the top of the said receptacle, a pipe connecting the chamber of the condenser at a point above the water-distributing means with the inlet of the pump, a tank 120 having an outlet at the top for any gaseous or aeriform fluid not soluble in water supplied to the tank, means for supplying water to the tank, a pipe arranged to conduct water and matter dissolved or diffused in the water from 125 the said tank, and a pipe connecting the water-receiving portion of the tank with the outlet of the pump.

3. The combination, with a receptacle wherein gases and vapors arise or emanate 130 from material treated therein, of a pump, a condenser having a water-receiving chamber, a well or reservoir at an elevation below the condenser, a drain-pipe extending from the

- lower end of the said chamber into the well or reservoir, means for distributing water within the said chamber a suitable distance above the drain-pipe, a water-supply pipe arranged to feed water to the water-distributing means, a pipe connected with the aforesaid chamber between the drain-pipe and the water-distributing means and in open relation with the chamber of the first-mentioned 5 receptacle at the top of the said receptacle, a pipe connecting the chamber of the condenser at a point above the water-distributing means with the inlet of the pump, a tank having an outlet at the top for any gaseous or aeriform 10 fluid not soluble in water supplied to the tank, means for supplying water to the said tank, a pipe arranged to conduct liquid from the aforesaid tank and connecting the upper portion of the tank with the aforesaid well or 15 reservoir, a perforated pipe-section within the lower portion of the said tank, and a pipe discharging into the said perforated pipe-section and in open relation with the outlet of the pump. 20
- 25 4. The combination, with the receptacle wherein gases and vapors arise or emanate from material treated therein, of a pump; a condenser having a water-receiving chamber; a well or reservoir at an elevation below the 30 condenser; a drain-pipe extending from the lower end of the said chamber into the well or reservoir; means for distributing water within the said chamber a suitable distance above the drain-pipe; a water-supply pipe arranged to feed water to the water-distributing means; a pipe connected with the aforesaid chamber between the drain-pipe and the water-distributing means and in open relation with the chamber of the first-mentioned 35 40 receptacle at the top of the said receptacle; a pipe connecting the chamber of the condenser at a point above the water-distributing means with the inlet of the pump; a pipe arranged to conduct off liquid; gas-consuming means; a tank communicating, a suitable distance above its bottom, with the receiving end of the last-mentioned pipe; a pipe extending to the gas-consuming means from and in open relation with the said tank at the top of the 45 tank; a valved pipe connecting the chamber of the said tank with the aforesaid water-supply pipe, and a pipe connecting the water-receiving portion of the last-mentioned chamber with the outlet of the pump. 50
- 55 5. The combination, with the receptacle
- wherein material is dried or rendered or reduced, which receptacle has an outlet for gases and vapors emanating or arising from material treated therein, of a pump connected with the said vapor-outlet; a condenser arranged in the line of the passage of gases and vapors from the said vapor-outlet to the pump; a furnace; a pipe arranged to feed gases and air to the furnace; a pipe arranged to conduct off liquid; a tank having its chamber in open relation, at the top, with the furnace-feeding pipe and communicating also with the receiving end of the aforesaid liquid-conducting pipe; means for supplying water to the tank, and a pipe connecting the water-receiving portion of the chamber of the tank with the outlet of the pump. 60 65 70
6. The combination, with a receptacle for supplying gases and vapors, which receptacle has an outlet for gases and vapors; of a pump connected with the said vapor-outlet; a condenser arranged in the line of the passage of gases and vapors from the said vapor-outlet to the pump, which condenser has a downwardly-extending drain-pipe for conducting off liquid resulting from condensation or liquefaction of gases and vapors within the condenser; a pipe adapted to connect with and feed a sewer and having its receiving end arranged above the discharging end of the 80 aforesaid drain-pipe; a well or reservoir communicating with the lower end of the said drain-pipe and in open relation with the sewer-feeding pipe; gas-consuming means; a pipe arranged to feed gases and air to the 85 said gas-consuming means; a pipe or passage-way connecting with and discharging into the said well or reservoir; a tank having its chamber communicating with the last-mentioned pipe or passage-way and also in open relation, 90 at the top, with the pipe arranged, as aforesaid, to feed the gas-consuming means; means for supplying water to the said tank, and a pipe connecting the water-receiving portion of the chamber of the tank with the outlet of 95 the pump. 100

In testimony whereof I sign the foregoing specification, in the presence of two witnesses, this 8th day of January, 1902, at Cleveland, Ohio.

EUGENE R. EDSON.
